US0D1073727S

(12) **United States Design Patent** (10) Patent No.: **US D1,073,727 S**
 Ye et al. (45) Date of Patent: ** May 6, 2025

(54) **DISPLAY SCREEN OR PORTION THEREOF WITH GRAPHICAL USER INTERFACE**

(71) Applicant: **HTC Corporation**, Taoyuan (TW)

(72) Inventors: **Zong Yan Ye**, Taoyuan (TW); **Chieh Lin Yen**, Taoyuan (TW)

(73) Assignee: **HTC Corporation**, Taoyuan (TW)

(**) Term: **15 Years**

(21) Appl. No.: **29/929,615**

(22) Filed: **Feb. 22, 2024**

Related U.S. Application Data

(62) Division of application No. 29/724,557, filed on Feb. 18, 2020.

(30) **Foreign Application Priority Data**

Dec. 13, 2019 (TW) 108307751

(51) **LOC (15) Cl.** **14-04**

(52) **U.S. Cl.**

(57) **CLAIM**

The ornamental design for a display screen or portion thereof with graphical user interface as shown and described.

DESCRIPTION

FIG. 1 is a front view of a display screen or portion thereof with graphical user interface according to our new design; and,

FIG. 2 is an additional view of FIG. 1 but shown with the broken lines illustrating portions of the graphical user interface removed for clarity of illustrating the claimed design. The dot-dash broken lines showing the display screen or portion thereof no part of the claimed design. The dashed broken lines showing portions of the graphical user interface form no part of the claimed design.

1 Claim, 2 Drawing Sheets
